UNITED STATES PATENT OFFICE.

EDWARD B. GREEN, JR., OF BUFFALO, NEW YORK.

FOLDING WHEEL-CHAIR.

1,206,106.

Specification of Letters Patent. Patented Nov. 28, 1916.

Application filed February 4, 1916. Serial No. 76,174.

To all whom it may concern:

Be it known that I, EDWARD B. GREEN, Jr., a citizen of the United States, and a resident of Buffalo, Erie county, and State 5 of New York, have invented certain new and useful Improvements in Folding Wheel-Chairs, of which the following is a full, clear, and exact description.

The invention aims to provide a stanch 10 trundle chair, collapsible at will to fold within narrow compass for easy storage in car or closet, as may often times be necessary.

The precise nature of the improvement 15 will appear in detail from the description following and be more exactly pointed out by claims at its conclusion.

On the drawings, Figure 1 is a view of the improved chair extended in side elevation, the dotted lines showing the position 20 assumed by certain of the parts when collapsed. Fig. 2 a view in cross-section on line 2—2 of Fig. 3 and Fig. 3 a detail in longitudinal section at line 3—3, Fig. 2, to 25 display the junction of the upright front leg with the arm-rest slidably hinged thereto. Fig. 4 a front elevation view of the chair extended. Fig. 5 a detail section at the pivot union of the front leg with the 30 seat stretcher. Fig. 6 a like view at the latch junction of the stretcher with the sloping side rail. Fig. 7 fragmentary plan of the same seat bottom as extended between the upright leg and the side rail in cross- 35 section, respectively.

In the form shown by Figs. 1 and 4, the dual side rails *a* support between them the back *b* stoutly secured thereto by bolts *c*, the rails being sustained below in turn by 40 trundle wheels *e* mounted on cross-axle *d* boxed to the sloping rails nearly under the center of gravity for the system turning about axle *d*. The side rails curve forward beneath the seat frame, and are united at 45 front by a horizontal foot rest *f*, to complete with back *b* a stout frame for the burden. Upright legs *g* hinged at *h* near the terminals of sloping rails *a*, sustain at cross rod *g* the front part of the seat frame for 50 the patient while on their flat tops they slidably carry by leaf hinges *j* the dual arm rests *i* which latter fasten in turn at back hinges *j* to the companion side rails *a*.

As appears in Figs. 2 and 3, the under 55 face of each arm-rest *i* is channeled lengthwise to allow for easy play of a guide plate

k held flat within the channel *l* by upright bolts *m* projecting from the horizontal member of leaf-hinge *j*. Yielding washers *n* of rubber or the like, carried upon the shanks of bolts *m* bear upon the retainer plate or keeper *o*, fastened by screws under each arm to close the channel but slotted lengthwise far enough to afford sufficient travel for internal guide plate *k* when the 60 chair is either collapsed or distended by the operator.

A seat frame or stretcher *p*, suitably located below the arm-rests *i*, is pivotally sustained by cross-rod *q* (Figs. 1, 4, 5) from 70 front legs *g* and yet is free to latch or unlatch at will by means of open catches *r* secured under the frame in position to interlock with the supporting rod *s* extended cross-wise at proper level between the side 75 rails *a*.

If the chair be in open or extended position shown by full lines, Fig. 1, the operator with one hand sustains the curved rails *a* upright on wheels *e* while with the other 80 hand, he releases seat stretcher *p* at catch *r* and forces back the front legs *g* turning at hinges *h*. Responsively, during the turn of legs *g*, the seat frame *p* pivoted thereto at *q*, travels upward at its free rear end. Simultaneously, arm-rests *i* slidably united to legs *g* at leaf-hinges *j*, gradually fold down about rear hinges *j* until the parts in collapsed state assume the relative position denoted by dotted lines, Fig. 1. A reverse 85 movement of front legs *g*, unfolds the chair parts until the seat *p* in free descent at back encounters cross rod *s* and being forced on to catches *r* stretches taut the junction of the uplifted arm rests *i* over the raised 90 front legs *g*. In open or unfolded state, the upright front legs *g* present their flat tops to contact against the underface of each arm rest *i* brought to a level under taut strain to prevent rickety displacement on 95 stop contact, for example, of guide plate *k* with the end of channel way *l*.

Ordinarily, the wheels *e* for trundling the chair are of sufficient diameter to comfortably mount the risers from step to step 100 of the usual flight of stairs. In such use, the chair with its burden is tipped backward slightly about cross-axle *d* by one attendant who grasps the upper extension handles of side rails *a* while his companion 105 seizes the lower foot rest *f* upturned by the tilt for easy hand-hold. Between them, the 110

chair and its burden can ascend or descend, step by step, with utmost ease, due in measure to the size of trundle wheels *e* and the position thus assured for their sustaining axles to better balance the load in easy poise about the center of gravity.

The curved rails *a* are generally made from a single piece of bent wood to afford a stiff, rigid mount at the cross-axle *d* of wheels *e*. Although the single axle serves also as a stretcher rung it is obvious that the separate wheels can each have a distinct axle stem, if desired.

Other modifications suggested by the mechanic's skill can be effected without departure from the limits of the improvement.

Having thus described my invention, what I claim as new and desire to secure by Letters Patent is:—

1. In folding wheel-chairs, the combination with a set of trundle wheels, of dual curved side rails carried thereby and sloping forward practically to a horizontal level, a stretcher foot rest extended cross-wise between the rails, companion front legs hinged upright to the side rails below, companion arm rests pivoted to the same

rails above and hinged at front in sliding union with the tops of said upright legs 30 and a seat frame pivoted to the upright legs intermediately, the frame being latched to the side rails behind for taut stretch or collapsible release of the sliding union between the arm rests and the upright legs, at will 35 of the operator.

2. In folding wheel-chairs, the combination with a set of trundle wheels, of dual curved side rails carried thereby and sloping forward practically to a horizontal 40 level, a stringer extended cross-wise between the rails, companion front legs hinged upright to the side rails below, companion arm rests pivoted to the same rails above and hinged at front in sliding union with the 45 flat tops of said upright legs and a stretcher frame pivoted to the upright legs intermediately but latched to the side rails behind for taut stretch or collapsible release of the sliding union between the arm rests 50 and the upright legs.

EDWARD B. GREEN, JR.
